UNITED STATES PATENT OFFICE.

JAMES D. TEW, OF HUDSON, OHIO, ASSIGNOR TO THE B. F. GOODRICH COMPANY, OF NEW YORK, N. Y., A CORPORATION OF NEW YORK.

METHOD OF PROLONGING THE LIFE OF EXPANSIBLE VULCANIZING CORES.

Application filed July 1, 1922. Serial No. 572,255.

To all whom it may concern:

Be it known that I, JAMES D. TEW, a citizen of the United States, residing at Hudson, in the county of Summit and State of Ohio, have invented a certain new and useful Method of Prolonging the Life of Expansible Vulcanizing Cores, of which the following is a specification.

This invention relates to the art of vulcanizing pneumatic tire casings on expansible cores or bags, commonly known as air bags or water bags. These bags have usually been made either of layers of rubberized fabric or of a thick wall of soft rubber reinforced with fabric at the base. I have obtained better results with the latter type of bag than the former, one advantage among others being that owing to its thick but pliable wall, deterioration can be observed and the bag taken out of service before it bursts with the possible result of ruining an entire heat of tires through vulcanizing them without any internal pressure.

It is the object of my invention to prolong the life of bags of this class, and especially those of the thick-walled rubber variety, and to that end I have devised a plan of renewing the outer surface of the bag after it has become hardened or over-vulcanized and has begun to crack but preferably before the main body of the bag-wall has become substantially hardened or deeply cracked. This may be done by scraping off the hardened crust and substituting a fresh coating of rubber having no sulphur or less than a vulcanizing content of sulphur. I do not broadly claim a vulcanizing bag of this construction, but the employment of such a veneer in carrying out my invention is found to give good results.

Of the accompanying drawings:

Fig. 1 is a side view of a part of a rubber, tire-vulcanizing bag which to a degree has deteriorated, as above mentioned.

Fig. 2 is a perspective view of the bag illustrating one step in my method.

Fig. 3 is a side view of a part of the bag as it appears at a later stage.

Fig. 4 is a view in section and perspective of the bag as it appears after the application of my method thereto.

Referring to the drawings, 10 is the body of the bag and 11 indicates the checked or cracked condition of its outer surface resulting from successive tire-vulcanizing opera-

tions. 12 is the base portion of the bag, which is of thick-walled construction and not adapted to stretch substantially in the vulcanizing of the tire and is therefore less subject to the defects referred to as being present in other parts of the bag. 13 is the stem mounted in the base-portion 12 for conducting pressure fluid into the bag.

In practicing my method I remove the deteriorated material 11 from the body of the bag, preferably by abrading or buffing, as with a rasp 14 or other suitable tool, exposing the underlying, substantially unaffected, portion 15, to which the sulphur has not penetrated in such quantities as to cause over-curing or excessive loss of elasticity. The material is preferably removed to substantially the same depth over the entire crown of the bag, such depth depending upon the depth to which the worst of the cracks have penetrated, the bag then having the appearance shown in Fig. 3, with a more or less rough surface, depending upon the character of the means used in removing the last of the abraded material. I then apply a sheet of unvulcanized rubber 16 to the newly exposed surface of the bag, preferably with an intervening layer of rubber cement (not shown) where it may be permanently and more firmly secured by subsequent heating and pressing in use or, preferably, by the application of heat and pressure, by any suitable means, as by expanding the bag in a suitable vulcanizing mold, before further use. The bag may be repeatedly re-covered from time to time, in this way, and its life greatly prolonged at comparatively small expense, the new rubber, 16, shielding the main body of the bag from sulphur emanating from successive tires.

The sheet of new rubber, 16, preferably is of a compound containing a small amount, but less than the usual vulcanizing percentage, of sulphur, so that it may absorb a substantial quantity of sulphur from successive tires in the curing operation before becoming over-cured and so requiring to be removed. I do not wholly limit my invention, however, to the use of such paucity of sulphur, or to the use of any sulphur, initially, in said sheet, nor do I otherwise limit it except as required by the prior art or as defined in the appended claims.

The term "rubber" as applied in the claims to the material composing the wall of the

bag includes, unless otherwise limited, rubberized fabric.

I claim:

1. In the art of vulcanizing pneumatic tire casings on fluid-expansible, rubber cores, the method which comprises using the core in repeated vulcanizations until a hardened crust has formed on its outer surface, removing said crust, substituting a fresh rubber coating, and using the core in further vulcanizations. 45
  2. In the art of vulcanizing pneumatic tire casings on fluid-expansible, rubber cores, the method which comprises using the core in repeated vulcanizations until a hardened crust has formed on its outer surface, abrasively removing said crust, substituting a fresh rubber coating, and using the core in further vulcanizations. 50
  3. In the art of vulcanizing pneumatic tire casings on fluid-expansible, rubber cores, the method which comprises using the core in repeated vulcanizations until a hardened crust has formed on its outer surface, removing said crust, substituting a fresh rubber coating containing less than a normal vulcanizing percentage of sulphur, and using the core in further vulcanizations. 55
  4. In the art of vulcanizing pneumatic tire casings on fluid-distensible cores having thick walls composed primarily of an underbody of soft vulcanized rubber and a veneer of originally unvulcanized rubber, the method which comprises using said core in repeated vulcanizations until the veneer has become over-vulcanized, removing the hardened veneer, and applying to the core a fresh, unvulcanized rubber veneer. 65
  5. In the art of vulcanizing pneumatic tire casings on fluid expansive, rubber cores, the method which comprises using the core in
- repeated vulcanizations until a hardened crust has formed on its outer surface, removing said crust before cracks have deeply penetrated the body of the core, substituting a fresh coating of unvulcanized rubber, and using the core in further vulcanizations. 75
6. In the art of vulcanizing pneumatic tire casings on fluid-expansible, rubber cores, the method which comprises using the core in repeated vulcanizations until a hardened crust has formed on its outer surface, abrasively removing said crust before cracks have deeply penetrated the body of the core, substituting a fresh, unvulcanized rubber coating, and using the core in further vulcanizations. 80
7. In the art of vulcanizing pneumatic tire casings on fluid-expansible, rubber cores, the method which comprises using the core in repeated vulcanizations until a hardened crust has formed on its outer surface, removing said crust before cracks have deeply penetrated the body of the core, substituting a fresh, unvulcanized rubber coating containing less than a normal vulcanizing percentage of sulphur, and using the core in further vulcanizations. 85
8. In the art of vulcanizing pneumatic tire casings on fluid-distensible cores having thick walls composed primarily of an underbody of soft vulcanized rubber and a veneer of originally unvulcanized rubber, the method which comprises using said core in repeated vulcanizations until the veneer has become over-vulcanized, removing the hardened veneer before cracks have deeply penetrated the rubber under-body, and applying to the core a fresh unvulcanized rubber veneer. 90

In witness whereof I have hereunto set my hand this 27 day of June, 1922.

JAMES D. TEW.
